UNITED STATES PATENT OFFICE.

CHARLES W. HUNT, OF WEST NEW BRIGHTON, NEW YORK.

CAR-COUPLING.

SPECIFICATION forming part of Letters Patent No. 444,955, dated January 20, 1891.

Application filed November 17, 1890. Serial No. 371,670. (No model.)

To all whom it may concern:

Be it known that I, CHARLES W. HUNT, a citizen of the United States, residing at West New Brighton, in the county of Richmond 5 and State of New York, have invented an Improvement in Car-Couplings, of which the following is a specification.

Coupling devices for cars have heretofore been made with swinging knuckles adapted 10 to engage with each other when the cars are pressed toward each other, and these couplings are usually known as the "Janney" coupler. These couplings are connected to the cars by tail-pins, and a certain amount of 15 lateral springing movement is allowed to each coupling within the stirrup that is fastened to the under side of the car-platform, and this lateral motion has to be greater with cars that pass around curves of comparatively 20 short radius, in order that the couplings may remain properly engaged with each other and be free to maintain a straight position between the two tail-pins.

Where couplings of this general character 25 are made use of, especially upon cars that run upon curves of short radius, difficulty is experienced in properly coupling the cars by backing or running them together when standing upon a curve, because the tendency 30 of the pressure of one coupling against the other is to throw the couplings into an angular position toward the outer side of the curve, and this prevents the knuckles properly engaging with each other and the parts are liable to be broken or not to couple. 35

The object of the present invention is to bring the couplings into line with each other when the cars are run together, whether the cars are upon a straight track or upon a 40 curved track; and with this object in view the coupler-jaws are extended laterally with flat or nearly flat faces. Hence when the cars are run together the pressure of one lateral face against the other swings the couplers laterally and brings them into line, so that the couplers are maintained in their proper position after they are coupled and while the train is being backed, either upon a straight line or around a curve, and the lat-

eral strain heretofore existing that has tended 50 to break or injure the coupling-hooks is entirely avoided.

In the drawings, Figure 1 is a plan view representing two of the couplers in the position they occupy when the cars are upon a 55 curve and being run together for coupling, and Fig. 2 is a similar view of the couplers when connected.

The draft-bar or coupler A is pivoted upon the tail-pin B and the coupler passes through 60 the strap or stirrup C, as usual, and this strap or stirrup is sufficiently wide to allow for the requisite swinging movement of the coupler upon the tail-pin, and at the ends of the coupler there are suitable knuckles or hooks 65 D, which engage with each other when the cars are run together. These knuckles or couplers are shown of the character known as the "Janney" coupler, or they may be 70 hooks or knuckles of any suitable kind which engage with each other, and the head or jaw of each coupler is provided with lateral projecting plates or faces E F, which are in a plane at right angles to a central plane passing through the tail-pin B, and these faces E 75 F are located in such a manner in relation to the knuckles or coupling-hooks D that when such coupling-hooks are engaged with each other the plates E and F are in contact, or nearly so, and there is always a small amount 80 of looseness or play in the coupling-hooks or knuckles, so that these faces E and F may press flatwise against each other when the train is being backed, or the pressure may be 85 on the knuckles themselves, and when the cars are being run together for connecting the couplers the plates E and F may strike each other toward either one edge or the other when the couplers are at an inclination horizontally to one another, as in Fig. 1, and 90 the couplers will be swung into line with each other by the pressure upon such faces E F, and this is especially advantageous, as aforesaid, when the cars are upon a curved track at the time they are run together and automatically coupled.

I claim as my invention—

1. The automatic car-coupler provided with

interlocking hooks or knuckles, in combination with the faces E and F, extending laterally from the head of the coupler and at right angles to the center line of such coupler, substantially as set forth.

5. 2. The combination, with the interlocking knuckles or hooks, of a coupler-bar having a head with laterally-projecting faces E F, that bring the couplers into line with each other

when pressed together, substantially as set forth.

Signed by me this 10th day of November, 1890.

CHAS. W. HUNT.
